FLIER

Thomas Harris, Providence, R. I., assignor to
Harris Textile Machinery Corporation, a cor-
poration of Rhode Island

Application May 13, 1937, Serial No. 142,355

9 Claims. (Cl. 118—57)

This invention relates to a flier for roving or similar use; and has for one of its objects the provision of a flier which may be inexpensively formed and yet be effective and efficient in its operation.

5 Another object of the invention is the provision of a flier which is so constructed that it may be molded from plastic material such as Bakelite or the like.

10 Another object of the invention is the formation of a flier in which the various parts are balanced that relatively high speed operation may be had without detrimental vibration.

15 Another object of the invention is the leading of the work into the flier in such a manner as to protect the work against windage due to rapid rotation.

20 Another object of the invention is to construct the flier in such a manner that it may be easily and quickly threaded.

25 Another object of the invention is the arrangement of a presser foot through which the work is guided that the same may be moved against the yarn package by reason of centrifugal force.

With these and other objects in view, the invention consists of certain novel features of construction, as will be more fully described, and particularly pointed out in the appended claims.

In the accompanying drawing:

Fig. 1 is an elevation showing the flier in its relation to a bobbin which is mounted on a traverse rail;

Fig. 2 is a sectional view of the flier and its operating mechanism;

Fig. 3 is a fragmental view looking at the inside of the flier on substantially line 3—3 of Fig. 2, the same being broken and foreshortened to bring out the mounting of the tube at both its upper and lower ends;

Fig. 4 is an elevational view of the flier looking at the slotted side thereof;

Fig. 5 is a sectional view on substantially line 5—5 of Fig. 6;

Fig. 6 is a section on line 6—6 of Fig. 2;

Fig. 7 is a sectional view of a fragmental portion of the cylindrical flier showing the mounting of the guide tube therein;

Fig. 8 is a top plan view of the presser foot as mounted on the tube which is shown in section as taken on substantially line 8—8 of Fig. 2.

50 In the drawing and winding of roving, it is desirable to protect the roving as much as possible from windage and ballooning as it is packaged, which I accomplish by a cylindrical flier enclosing the work; and in order that such a flier may be formed inexpensively and yet be balanced properly for high speed operation, I have arranged to mold the flier from Bakelite or some similar synthetic material which may be produced with the desired smooth finish and with portions thickened

and recessed as desired for the accomplishment of different desired functions of the device; and the following is a more detailed description of the present embodiment of this invention, illustrating the preferred means by which these advantageous results may be accomplished:

With reference to the drawing, 10 designates generally a cylindrical flier formed of Bakelite or some similar synthetic material which may be molded with a smooth outer surface and in the desired shape to form side walls 11 and an end wall 12. A metal plate 13 is molded into the top wall 12 of the flier with its portions undercut so that the molded material may embrace the same as at 14 to hold the plate firmly embedded therein. An opening 15 is provided in the Bakelite portion of this top wall for the reception of a driving shaft 16 and its collar 18 which is fixed thereon with a portion of the shaft 16 beyond the collar extending through a smaller opening 17 in the plate 13 against which the collar abuts as at 19 and is locked to the plate as at 20 so as to positively cause the flier to turn with the shaft 16 and its collar 18 fixed thereto. A nut 21 on the reduced threaded end of the shaft 16 holds the flier firmly in position on the shaft. 25

A recess 22 is formed in the outer surface of the end wall which registers with the work opening 23 in the collar and opening 24 in the shaft through which the roving 26 passes so as to be below the outer surface of the end wall and thus be protected against windage due to rapid revolving of the flier. A hole 25 at the juncture of the side wall and end wall and registering with the recess 22 is formed for the work which is indicated by the dot-dash line 26 to pass therethrough into the interior of the flier. A slot 27 extending downwardly through the side wall of the flier from the recess 22 is formed with its trailing edge inwardly beveled as at 28, while its leading edge 29 is substantially radial of the cylinder. 35

A cylindrical tube 30 is rotatably mounted in a recess in the wall 11 with its upper end in an enlarged portion 31 of the opening 25 with the stock 32 of the cylinder enlarged by being swelled inwardly to receive and provide a bearing for this upper end of the tube 30. This stock is cut away in the form of a V as at 33 and a finger 34 is fixedly mounted on the upper end of the tube 30 and may swing between the surfaces of this notch 33 to limit the rotative movement of the tube to substantially 90°. 45

The lower end of the tube is provided with a bearing formed by a metal plate 35 which has a pair of lugs 36 fitting within recesses 37 on the inner wall of the tube and rotatably receiving in a recess 38 the lower end of the tube 30. This plate is held in position by screws 39 passing through the wall of the flier and entering threaded holes in the plate 35. A stop 40 is fixed to the 60

tube and engages the upper edge of the plate 35 to hold the tube against sliding outwardly from cylinder, while a presser foot 41 has a boss 42 mounting it on the tube 30 with an end 43 having an opening 44 therein for receiving and guiding the roving 26 onto the bobbin 48 of the machine. The tube 30 is slotted as at 45 while the boss 42 is slotted as at 46, which slots register with the slot 27 of the cylindrical body when 10 the presser foot is swung abnormally outwardly so that the yarn 26 may be drawn through the slots into the center 47 of the tube, after which the presser foot may be swung inwardly into close proximity to the bobbin 48, as winding occurs, 15 which movement moves the slots out of registry and prevents the yarn or roving from escaping from the tube.

In order to force the presser foot inwardly against the bobbin a lever 50 is pivoted as at 51 to the plate 13 which is molded into the top wall and is provided with a suitable weight 52 thereon, while its end has a hook portion 53 which engages the finger 34 on the upper end of the tube 30. Thus, as rotation occurs the weight 52 being greater than the weight of the presser foot is caused by centrifugal force to swing outwardly with reference to the axis of rotation and force the presser foot inwardly against the bobbin.

The plate 13 is of an irregular shape with a portion 55 at one side of the axis to balance the centrifugally acting weight 52, while the cylindrical body itself is thickened as at 56 to balance the weight of the tube 30, and thus it will be apparent that the thickness of the Bakelite body is 30 such as to provide the proper balance for the flier that a high number of revolutions per minute may be had without vibration.

The device being made of Bakelite presents a very smooth finish and surface over which the 40 yarn may travel without abrasion and also without materially wearing the Bakelite due to the inherent lubricating properties of the same.

In order to drive this flier, suitable gears 57 are provided on the shaft 16 which are driven 45 through gear 58 by gear 59 on the shaft 60 which is driven in turn by the spiral gear 61 from some suitable source of power. The bobbin 48 is driven on spindle 62 also from some suitable source of power, the same being mounted upon the traversing rail 63, all as more fully described in my co-pending application, Serial No. 137,683, filed April 19, 1937.

The foregoing description is directed solely towards the construction illustrated, but I desire 55 it to be understood that I reserve the privilege of resorting to all the mechanical changes to which the device is susceptible, the invention being defined and limited only by the terms of the appended claims.

60 I claim:

1. A flier for a spinning machine, comprising a hollow cylindrical body having side and end walls with an opening at substantially the juncture of these walls for the work to pass through, said end wall having a recess in its outer surface leading radially inwardly from said opening for the reception of the work as it passes into said opening.

2. A flier for a spinning machine, comprising 70 a hollow cylindrical body having side and end walls with an opening at substantially the juncture

ture of these walls, a slot through the side wall extending lengthwise of the body, and means within the body to guide the work.

3. A flier for a spinning machine, comprising a hollow cylindrical body having side and end walls with an opening at substantially the juncture of these walls, a slot through the side wall extending lengthwise of the body, and a guide tube within the body to receive and direct the work.

4. A flier for a spinning machine, comprising a cylindrical body having side and end walls with an opening at substantially the juncture of these walls, a slot through the side wall extending lengthwise of the body, and a guide tube within the body provided with a longitudinally extending slot to register with the slot in the body and receive the work when in one position of rotation, said slots being movable out of registry to prevent escape of the work from the tube.

5. A flier for a spinning machine, comprising a cylindrical body having side and end walls with an opening at substantially the juncture of these walls, a slot through the side wall extending lengthwise of the body, a guide tube within the body provided with a longitudinally extending slot to register with the slot in the body and receive the work when in one position of rotation, said slots being movable out of registry to prevent escape of the work from the tube, a presser foot at the lower end of the tube, said slots being so arranged that the slots are out of registry when the presser foot is in working position.

6. A flier for a spinning machine, comprising a cylindrical body having side and end walls with an opening at substantially the juncture of these walls, a slot through the side wall extending lengthwise of the body, a guide tube within the body to receive and direct the work, a presser foot at the lower end of the tube to engage the package as formed, and means actuated by centrifugal force to move the presser foot toward the package.

7. A flier for a spinning machine, comprising a cylindrical body having side and end walls with an opening at substantially the juncture of these walls, a slot through the side wall extending lengthwise of the body, a guide tube within the body to receive and direct the work, a presser foot at the lower end of the tube to engage the package as formed, a weighted lever arm mounted on the inner side of the end wall, and means connecting said arm and tube to rotate the tube and move the presser foot toward the package.

8. A flier for a spinning machine, comprising a cylindrical body having side and end walls with an opening at substantially the juncture of these walls, a slot through the side wall extending lengthwise of the body, and a guide tube within the body to receive and direct the work, said side wall being of unequal thickness with a thicker portion diametrically opposite the tube to counterbalance the weight of the tube.

9. A flier for a spinning machine, comprising a cylindrical body having side and end walls of molded non-metallic material, operating parts within the body, a plate molded into the end wall of the body with portions so located with reference to the central axis of the body as to balance operating parts carried by the body.

70 THOMAS HARRIS.
